UNITED STATES PATENT OFFICE.

JOHN EDSON BOYNTON, OF CHICAGO, ILLINOIS, ASSIGNOR TO WESTERN ELECTRIC COMPANY, INCORPORATED, OF NEW YORK, N. Y., A CORPORATION OF NEW YORK.

METHOD OF AND MEANS FOR HANDLING MATTER.

Application filed May 8, 1924. Serial No. 711,763.

This invention relates to a method of and means for handling matter which is sufficiently plastic in one state so that it may be pumped from one receptacle into another, and more particularly to a method of and means for extruding matter.

The primary object of the invention is to provide a method of and means for effecting a continuous extrusion of matter.

Other objects of the invention are to extrude matter by continuously receiving a supply of it in one state, changing it into a different state, and then causing it to emanate continuously from an aperture at a rate substantially proportional to the rate at which it is received and to provide an improved method of and improved means for continuously forming pipes and tubing; to provide an improved method of and improved means for continuously sheathing a cable.

A preferred form of the invention is embodied in an extruding machine for sheathing cable cores and comprising a plurality of pumps which receive fused metallic matter from a common supply thereof and force the fused matter into an annular chamber, the annular chamber having a discharge opening. A die is adjustably supported with respect to the discharge opening. A core tube projecting into the annular chamber and aligned with the die provides means by way of which a cable core may pass through the chamber so that matter forced into the annular chamber by the pumps will sheath the core, the machine being so designed that the matter reverts to its solid state before it comes into contact with the core.

The core when it leaves the extruding machine is enclosed in a sheath of the solidified matter. The several pumps are disposed around the axis of the annular chamber in such manner that substantially equal pressures are obtained in all parts thereof so that the matter extruded from the machine is of substantially uniform density and texture. The pumps preferably comprise cylinders which project from a housing surrounding the annular chamber. The inner

ends of the cylinders communicate directly with the annular chamber. The outer ends of the cylinders are free to move when the cylinders contract or expand in response to variations in the temperature thereof, or when the cylinders move radially with respect to the axis of the annular chamber during temperature changes in the extruding machine, as plungers slidably journaled in the cylinders are reciprocated by means mounted independently of the cylinders. This construction insures that deformation of the cylinders will not be occasioned when the temperature of the cylinders varies from the temperature of other parts of the machine.

The fused metallic matter is supplied to the pumps by way of a common manifold, the pumps comprising a plurality of check valves which are particularly adapted to control the flow of the fused matter to the pumps. Other valves are provided for preventing a back flow from the annular chamber to the pumps, and the pumps are so driven that fused matter is being forced continuously into the annular chamber whenever the machine is forming a sheath upon a cable core. The annular chamber comprises a cylindrical portion intermediate its ends, one of the ends being contracted to form the discharge opening and the other end being flared to receive the discharge openings of the pumps. The cylindrical portion of the annular chamber permits a relatively large quantity of matter to be stored under pressure in the chamber and permits the metal or the matter to be solidified at a point relatively remote from the discharge aperture, it being readily understood that the solidified matter can be displaced longitudinally in the cylindrical portion of the chamber with much less effort than it could be displaced in a chamber having converging walls. In line with the above construction, a plurality of means is provided for controlling the temperature of the matter as it passes along the cylindrical portion of the annular chamber, the means being regulatable to supply heat to or to withdraw heat from the matter being

extruded. These means permit the operator to cause a change in the state of the matter at any desired point in the annular chamber.

5 The pumps are packed by means of the matter being extruded, that is, a portion of the matter is solidified and employed to prevent leakage between the plungers and their respective cylinders. In one form of 10 the invention, the matter is collected and solidified in pockets formed in the cylinder walls, and in another form of the invention, each of the plungers is adapted to carry a quantity of the matter in a solidified state 15 in such a position that it prevents leakage between the plunger and its cylinder.

Other objects of the invention will become apparent as the detail description progresses, reference being had to the accompanying drawings, wherein 20

Fig. 1 is a central longitudinal section through an extruding machine which embodies the invention;

Fig. 2 is an end elevation of the extruding 25 machine looking from the left in Fig. 1;

Fig. 3 is a section taken on line 3—3 of Fig. 1;

Fig. 4 is an enlarged central longitudinal section of one of a plurality of pumps which 30 form parts of the extruding machine;

Fig. 5 is a section taken on line 5—5 of Fig. 4, and

Fig. 6 is a central longitudinal section 35 through a pump which, if so desired, may be employed in place of the pump shown in Fig. 4.

It is believed that a complete understanding of the improved method will be procured by a description of the means by 40 which it is performed.

Referring to the drawings wherein like reference characters designate like parts throughout the several views, the reference character 10 designates a base plate upon 45 which is mounted the mechanism of an extruding machine embodying the invention. The reference character 11 designates generally a head which is disposed at one end of the base plate 10 and is rigidly secured 50 thereto by a plurality of bolts 12. The head 11 comprises a tubular block 13, which together with a back plate 14, forms an annular chamber 15, the back plate 14 being rigidly secured to the tubular block 13 by 55 means of a plurality of bolts 16 (Fig. 3). It will be noted that the annular chamber 15 comprises a cylindrical portion 17 intermediate its ends, one of the ends being contracted to form a discharge opening 18, and 60 the other end being flared as at 19. The advantage of this construction will be explained hereinafter, but for the present it will suffice to state that the annular chamber 15 forms a passage for the matter to be 65 extruded, the discharge opening 18 of the

annular passage having associated therewith a core tube 20 and a die 21. The die 21 threadedly engages a die holder 22 and is provided at its outer ends with a plurality of flattened sides 23 adapted to receive a wrench, which may be used to bring the die into a plurality of adjusted positions with respect to the core tube 20. The die holder 22 is interposed between the tubular block 13 and a clamping plate 24 which may be 70 adjusted by means of a plurality of bolts 25 into a position wherein it exerts sufficient pressure upon the die holder 22 to prevent displacement thereof relative to the discharge opening 18. The clamping plate 24 carries means for laterally adjusting the die holder 22. This means comprises a plurality of bolts 26 which engage the periphery of the die holder and may be used to effect lateral adjustment of the die holder, 75 it being understood that it is necessary to loosen the bolts 25 when such lateral adjustment of the die holder 22 is to be made. It is apparent that the die holder 22, the clamping plate 24, and the associated bolts 80 25 and 26 constitute means whereby the die 21 may be adjusted laterally and longitudinally with respect to the axis of the core tube 20, the axis of the core tube 20 being coincident with the axis of the annular 85 chamber 15. This construction permits the die 21 to be aligned accurately with respect to the discharge opening, and at the same time permits the operator to control the cross-sectional area of a stream of matter 90 being extruded from the machine.

The core tube 20 may be adjusted longitudinally of its axis, the core tube being slidably and rotatably journaled in a sleeve 27 formed integral with the back plate 14. 105 The means for adjusting the core tube longitudinally of its axis comprises a sleeve 28 with which the core tube makes threaded engagement. The sleeve 28 is screw threaded into the sleeve 27 and at its rearwardly extending end is provided with a plurality of flattened surfaces 29 adapted to be engaged by a wrench which may be employed to bring the sleeve 28 and the core tube 20, as a unit into a plurality of adjusted positions with respect to the die 21. This construction also permits the core tube 20 to be replaced quickly and easily as the operator need only withdraw the sleeve 28 110 from the sleeve 27, replace the core tube 20 and then return the sleeve 28 to the sleeve 27. The advantage of this construction is 115 apparent.

As best shown in Fig. 1, the sleeve 28 and core tube 20 are adapted to accommodate a cable core 30 which may be drawn through the machine by any suitable means (not shown), or which may be drawn through the machine by matter being extruded from the machine. Since the die 21 may be brought 120 125 130

into a position wherein its axis is coincident with the axis of the core tube, it follows that any matter extruded by way of the discharge opening 18 will form a sheath of uniform thickness around the cable core. The cable core, of course, will be drawn through the machine at a rate of speed proportional to the rate of speed at which the matter is extruded between the core tube and the die.

- 10 The annular chamber 15 is continuously supplied with matter to be extruded, the matter being forced into the annular chamber under sufficient pressure to cause it to be extruded between the core tube and the die.
- 15 This means for supplying the annular chamber with matter to be extruded includes a plurality of pumps 31, each of the pumps 31 comprising a cylinder 32 having a substantially central bore 33. The axes of the 20 several cylinders 32 are disposed parallel to the common axis of the core tube 20, and of the die 21, the bores 33 of the cylinders opening directly into the flared end 19 of the annular chamber 15. As shown in Fig. 25 3, the axes of the cylinders 32 are substantially equi-distantly spaced from each other and approximately so from the common axis of the core tube and the die. Certain combinations of the cylinders are equi-distantly 30 spaced from each other and from the axis. Therefore, the cylinders of the pumps may be said to be disposed around the common axis, or may be said to be disposed around the annular chamber 15. Slidably journaled in each of the cylinders 32 is a 35 plunger 34 adapted to be reciprocated therein so that it may force matter, to be extruded, into the annular chamber 15. The matter to be extruded is supplied to the cylinders by way of a common manifold 35, which is preferably of substantially rectangular form and is connected to a receptacle 36 by means of a pipe 37 (Fig. 2). The receptacle 36 is adapted to hold a supply 40 of the matter to be extruded, suitable means (not shown) being provided to keep the matter in a fused state so that it may gravitate by way of the pipe 37 to the manifold 35, and thence to the cylinders 32. A 45 valve 38 disposed in the pipe 37 provides means whereby the operator may control the flow of fused matter to the cylinders.

50 A plurality of valve devices 40 prevent a back flow from the cylinders 32 into the manifold 35, one of the valve devices 40 being interposed between each of the cylinders 32 and the common manifold 35 (Fig. 4). Each valve device 40 is disposed in the in-take opening of its associated cylinder 32 and comprises a valve cage 41 threaded or otherwise tightly and securely fitted into the in-take opening. The valve cage 41 is provided with a central aperture 42, through 55 which the fused matter must pass on its way to the cylinder. Disposed beneath the aper-

ture 42 and retained in substantial alignment therewith is a solid ball 43 manufactured of matter of less specific gravity than that of the fused matter. It is obvious that the ball 43 will tend to float into a position 70 wherein it closes the aperture 42 whenever the cylinder holds a quantity of fused matter.

75 Means are also provided for preventing a back flow from the annular chamber 15 to the several cylinders 32. Thus each pump 31 is provided with a check valve 44, which comprises a valve cage 45 seated in the discharge opening of the pump, the valve cage 45 being adapted to retain a ball 46 in the 80 opening. The ball is adapted to engage a valve seat 47 formed in the opening.

85 From the foregoing detailed description of the pumps, it is apparent that if one of the plungers 34 is reciprocated in its cylinder, there will be an intermittent flow of fused matter from the receptacle 36 through the cylinder, and thence to the annular chamber 15, the balls 43 and 46 acting to control the flow of fused matter to and from 90 the cylinder. It is also apparent that the forward strokes of the several plungers 34 may be so timed relative to each other that a continuous flow of fused matter into the annular chamber 15 is obtained. In this embodiment of the invention the pumps are driven so as to continuously force fused matter in the annular chamber 15 during the 95 extruding operation.

100 The means for driving the pumps 31 comprises a shaft 50 which is adapted to drive two vertically disposed shafts 51 and 52 through the medium of a plurality of bevel gears 53, the shaft 50 being driven from any suitable source of power (not shown). The 105 vertically disposed shafts 51 and 52 are adapted to drive a horizontally disposed shaft 54, the shaft 54 being operatively connected to the vertically disposed shafts 51 and 52 by means of a plurality of bevel gears 110 55. The driven shaft 50 and each of the shafts 51, 52, and 54 is rotatably journaled into an upright standard 56 rigidly secured to the base plate 10 by a plurality of bolts 57. The standard 56 is securely held in 115 spaced relation with the head 11 by means of a plurality of threaded rods 58 which are rigidly secured to the standard by a plurality of nuts 59 and to the head by a plurality of nuts 60. Each of the several shafts 120 50, 51, 52, and 54 has rigidly secured to it a plurality of eccentrics 61, each eccentric 61 being aligned with one of the pumps 31. Each eccentric 61 is operatively connected to the plunger 34 of its associated pump 31 125 by means of an eccentric rod 62, and an eccentric strap 63. The free end of each eccentric rod 62 is pivoted upon a wrist pin 64 carried by a cross-head 65, which is rigidly secured to the outer end of the asso- 130

iated plunger 34. The cross-head 65 is journaled in a plurality of guides 66 rigidly secured to the outer end of the cylinder 32 of the pump. The guides are virtually integral with the cylinders so that they remain in perfect alignment at all stages of expansion of the machine in general. The eccentric strap 63 preferably comprises a cap 67 and is rotatably journaled upon its eccentric by means of a roller bearing which consists of a plurality of rollers 68 and a cage 69. The employment of the roller bearing between the eccentric and its strap is advantageous in that proper lubrication between the eccentric and the strap is insured, it being understood that the eccentrics carry comparatively large loads and that they would tend to drive out any lubricating oil or the like which might be introduced between them and their straps if the roller bearings were not provided. The several eccentrics 61 are so arranged relative to each other that fused matter is forced continuously into the annular chamber 15 when the extruding machine is in operation, the velocity for this continuous flow of fused matter being substantially constant when the machine is operated at a given speed. Of course the speed of the driven shaft 50 may be varied by means well known to those skilled in the art so that the rate of extrusion will correspond to the size of the core tube and its die or to other conditions obtaining at any particular time.

It will be noted that the outer ends of the cylinders 32 are free to move, when the cylinders contract or expand in response to variations in temperature and are also free to move when the back plate 14 contracts or expands, thus causing the cylinders to move in and out radially with respect to the axis of the annular chamber 15. As the guides 66 are mounted on the outer ends of the cylinders 32 and are not supported by any other means, they are also free to move when they or their respective cylinders move in response to variations in temperature. This construction is provided to prevent deformation of the cylinders 32 and distortion of the guides 66 when the temperature of the head 11 and the mechanism associated directly therewith varies from the temperature of the standard 56 and the driving mechanism mounted thereon.

Means is provided for packing each of the pumps 31, the means in each instance comprising a pocket or annular recess 70 (Fig. 4) turned in a collar 71 which is threaded into an enlargement of the bore 33 of the pump 60 and may be considered a portion of the cylinder thereof. The annular recess 70 is adapted to collect and retain any fused matter seeking to escape through the clearance which must be provided between each plung-

er and the wall of its associated cylinder. 65 The matter so collected tends to revert to its solid state, but to insure such a change of state, an annular chamber 72 is provided in the collar 71 into which a cooling fluid may be introduced by means comprising a plurality of nozzles 73 having central passages which connect the chamber 72 (Fig. 5). It is readily understood that flexible hose or the like (not shown) may be fitted over the nozzles 73 to connect the nozzles with any suitable supply of cooling fluid, and that means (not shown) may be provided for causing forced circulation of the cooling fluid through the annular chamber 72. Cooling fluid so introduced into the annular chamber 72 will lower the temperature of any fused matter collected in the annular recess 70 and cause it to solidify. The solidified matter will then pack the pump.

The pumps 31 are mounted in the head 11 in an improved manner, each pump comprising a frusto-conical head 74 adapted to seat in a similarly shaped aperture 75 formed in the back plate 14 (Figs. 1 and 4). Each pump is provided with a nut 76 threaded upon its cylinder and adapted to engage the back plate 14 to prevent displacement of the pump relative to the eccentric and also the manifold. The arrangement is such that the pressure which obtains in the annular chamber 15 tends to force the frusto-conical head against its seat, and as this construction permits the heads to be ground into the seats, it is obvious that a perfect seal will result in each instance, thus making it unnecessary to pack the heads.

Referring now to Fig. 1 the tubular block 11 is provided with a plurality of annular channels 77 to accommodate a plurality of coils 78 adapted to receive cooling or heating fluids whereby the temperature of the matter passing through the block may be controlled. By regulating the temperature of the fluid introduced into the coils 78, it is possible to solidify the fused matter at any desired point in the annular chamber 15. Thus the coils 78 associated with the flared end 19 of the annular chamber 15 could be supplied with a heating fluid to prevent solidification of the fused matter, and the remaining coils could be provided with a cooling fluid of proper temperature to cause the fused matter to revert to its solid state as it enters the cylindrical portion 17. A sufficient supply of a matter in its solid state would then be stored in the annular chamber to negative the possibility that any matter might pass out in its fused state through the extrusion aperture. Comparatively little power is required to move the solid matter along the cylindrical portion 17 because this portion of the chamber 15 has a constant cross-section.

Fig. 6 illustrates one of a plurality of pumps which may be employed in place of the pumps shown in Fig. 1. Thus a pump 79 is shown, which comprises a cylinder 80 having an extension 81, the cylinder 80 and the extension 81 having aligned bores 82 and 83 respectively. A plunger 84 adapted to reciprocate in the bore 83 carries means at its forward end for holding or retaining a quantity of the matter which is being extruded. The means preferably comprises a plurality of annular grooves 85 in which the matter may collect and solidify, the solidified matter being then held in a position wherein it packs the cylinder. Of course the pump is so designed that a comparatively low temperature will obtain in the extension 81 as compared with the temperature obtaining in the cylinder 80, and the plunger 84 is not brought into a position wherein the fused metal passing from the intake opening of the pump to the discharge opening thereof may fuse the matter solidified upon the forward end of the plunger. In Fig. 6 the plunger 84 is provided with a cross-head 86 slidably journaled in guides 87 rigidly secured to the cylinder 80. The guides 87 are so arranged that air may circulate about the extension 81 to keep it at a temperature below the temperature of the cylinder 80.

In the operation of the device a supply of the matter to be extruded is fused in the receptacle 36 and one end of the cable core 30 is threaded through the core tube 20 and the die 21, one end of the core being introduced into the core tube 20 by way of the sleeve 28. The valve 38 is then opened and the extruding machine set in operation. The fused matter flows to the several pumps 31 by way of the pipe 37 and the manifold 35, and the pumps force the fused matter into the flared end 19 of the annular chamber 15. The matter solidifies as it passes through the cylindrical portion 17 of the annular chamber and is formed by the core tube and the die into a sheath which encloses the cable core being drawn through the machine. This process is continuous as the receptacle 36 may be charged from time to time so that the pumps can continue indefinitely to force fused matter in the annular chamber 15. The length of the core and not the size of the receptacle 36 would in a manner determine the capacity of the extruding machine.

What is claimed is:

1. A method of extrusion, which consists in continuously transforming fused matter into a hollow article of solidified matter having a wall of uniform thickness throughout its length, and then continuously forcing the solidified matter through an extrusion aperture to reduce the thickness of the wall of the article by supplying additional fused matter under pressure at the end of

the solidified matter remote from the extrusion aperture.

2. A method of extrusion, which consists in continuously transforming fused matter into a tube of solidified matter, having a wall of uniform thickness throughout its length, and simultaneously reducing the diameter of the tube and the thickness of the wall thereof by supplying additional fused matter under pressure at a point on the solidified matter remote from the extrusion aperture.

3. A method of extruding a sheath for a core, which consists in continuously transforming fused matter into a tube, having a wall of uniform thickness of solidified matter throughout its length, and then extruding the tube upon a core in such manner as to simultaneously reduce the diameter and the wall thickness of the tube by supplying additional fused matter under pressure in contact with the solidified matter at a point remote from the extrusion aperture.

4. A method of extrusion, which consists in pumping separated predetermined quantities of fused material in continuously recurring cycles into a common chamber having an extruding aperture, solidifying the matter therein, and continuously forcing the solidified matter through the aperture by the introduction of fused matter into the chamber in contact with the solidified matter.

5. A method of extrusion, which consists in pumping fused matter from a plurality of points in continuously recurring cycles into a common chamber having an extruding aperture, solidifying the matter in the chamber, and continuously forcing the solidified matter through the aperture by the introduction of fused matter into the chamber in contact with the solidified matter.

6. A method of continuously extruding matter, which consists in introducing fused matter into a chamber having the same cross section for the greater part of its length, allowing said matter to solidify, and reducing the cross-section of the solidified matter through said chamber due to the force exerted by the continuous introduction of additional fused matter.

7. A method of continuously extruding matter, which consists in introducing fused matter into a chamber at a plurality of spaced points, allowing said matter to solidify, and forcing the solidified matter through said chamber by simultaneously forcing a plurality of independent portions of fused matter directly into the chamber.

8. A method of continuously extruding matter, which consists in introducing fused matter into a chamber at a plurality of spaced points, allowing said matter to solidify, and forcing the solidified matter through said chamber by simultaneously forcing a

plurality of portions of fused matter into the chamber from a point aligned with the extreme end thereof.

9. A method of extrusion, which consists in supplying matter under pressure to a chamber having an extrusion aperture, solidifying the matter therein into a plurality of separated portions, extruding one of the solidified portions through the aperture and utilizing another solidified portion for preventing leakage of the fused matter from the chamber.

10. A method of extrusion, which consists in supplying matter under pressure to a chamber having an extrusion aperture, solidifying a portion of the matter, extruding the solidified portion through the aperture, collecting another portion of the fused matter in a pocket adjacent another opening in the chamber, and solidifying the collected matter to prevent leakage of the fused matter through the opening.

11. In an extruding machine, a chamber having an extrusion aperture and a plurality of pumps disposed completely around the chamber for continuously supplying the chamber with fused matter, each pump being positioned to discharge directly into the chamber in a direction substantially parallel to the direction in which the matter passes through the aperture of the chamber.

12. In an extruding machine, an annular substantially cylindrical chamber, means for continuously supplying the chamber with matter being extruded and comprising a plurality of cylinders communicating directly with the chamber and having their axes disposed substantially parallel to the axis of the chamber, a plunger for each cylinder, and means for reciprocating the plungers to introduce fused matter into said chamber and force the previously admitted matter therethrough.

13. In an extruding machine, an annular chamber having an aperture for shaping the extruded matter, means for continuously supplying the chamber with matter being extruded, and comprising a plurality of cylinders having their axes disposed parallel with the axis of the chamber, the cylinders being substantially equidistantly spaced from each other and from the axis of the chamber, a plunger for each cylinder, and means for reciprocating the plungers.

14. In an extruding machine, a housing, a chamber therein, means for continuously supplying the chamber with matter to be extruded and comprising cylinders projecting from the housing, a portion of each cylinder being free to move when the housing expands and contracts, a piston disposed in each cylinder, and means for reciprocating the piston to introduce fused matter into said chamber and force the previously admitted matter therethrough.

15. In an extruding machine, a housing having a chamber therein, means for continuously supplying the chamber with matter to be extruded and comprising cylinders projecting from the housing, a portion of each cylinder being free to move when each cylinder expands or contracts, a piston for each cylinder and means independently supported with respect to each cylinder for reciprocating the piston.

16. In an extruding machine, an annular chamber having a cylindrical portion of constant cross-section intermediate its ends, one portion of the annular chamber being contracted to form a discharge opening, and means for continuously supplying the chamber with matter to be extruded.

17. In an extruding machine, an annular chamber having a cylindrical portion of constant cross-section intermediate its ends, one of the ends being contracted to form a discharge opening and the other end being flared, and a plurality of pumps communicating with the flared end for supplying the chamber with matter to be extruded.

18. In an extruding machine, a chamber having one portion thereof of constant cross-section, and a plurality of means communicating directly with one end of the chamber for continuously supplying it with matter to be extruded.

19. In an extruding machine, an annular chamber having a cylindrical portion intermediate its ends, one of the ends being contracted to form a discharge opening and the other end being flared, a plurality of pumps communicating directly with the flared end for continuously forcing matter to be extruded into the chamber, and a valve for each pump for preventing a back flow from the chamber into the pump.

20. In an extruding machine, an annular chamber having a cylindrical portion intermediate its ends, one of the ends being contracted to form a discharge opening and the other end being flared, and means for continuously supplying the chamber with matter being extruded and comprising a plurality of cylinders opening directly into the flared end, the cylinders having their axes disposed substantially parallel to the axis of the cylindrical portion of the chamber, a plunger for each cylinder, and means for reciprocating the plungers.

21. In an extruding machine, an annular chamber having a cylindrical portion intermediate its ends, one of the ends being contracted to form a discharge opening and the other end being flared, the length of the cylindrical portion being greater than that of the contracted portion, and means communicating directly with the flared end for continuously supplying the chamber with matter to be extruded.

22. In an extruding machine, an annular

- chamber having a cylindrical portion intermediate its ends, one of the ends being contracted to form a discharge opening and the other end being flared, the length of the cylindrical portion being greater than that of the flared portion, and means communicating directly with the flared end for continuously supplying the chamber with matter to be extruded.
23. In an extruding machine, an annular chamber having a cylindrical portion intermediate its ends, one of the ends being contracted to form a discharge opening and the other end being flared, and means for continuously supplying the chamber with matter to be extruded and comprising a plurality of cylinders opening directly into the flared end of the chamber, a plunger for each cylinder, means pivotally connected to the plungers for reciprocating the plungers, and means for supporting the last-mentioned means independently of the cylinders.
24. In an extruding machine, a housing having a chamber therein, the chamber having a cylindrical portion intermediate its ends, one of the ends being contracted to form a discharge opening and the other of the ends being flared, and means for continuously supplying the chamber with matter to be extruded and comprising cylinders projecting from the housing and communicating with the flared end of the chamber, the outer end of each cylinder being free to move when each cylinder expands or contracts, a plunger for each cylinder, and means supported independently of each cylinder for reciprocating the plunger.
25. In an extruding machine, a housing having a chamber therein, the chamber having a cylindrical portion intermediate its ends, one of the ends being contracted to form a discharge opening and the other of the ends being flared, and means for continuously supplying the chamber with matter to be extruded and comprising cylinders projecting from the housing and communicating with the flared end of the chamber, the outer end of each cylinder being free to move when each cylinder expands or contracts, a plunger for each cylinder, and means pivotally connected to the plunger and supported independently of each cylinder for reciprocating the plunger.
26. In an extruding machine, a chamber having an extrusion aperture, and means including a plurality of pumps disposed completely around the chamber for continuously supplying the chamber with matter and extruding said matter therefrom, each pump comprising an intake passage connected with a supply of said matter, a valve seat in the passage, and a valve member of less weight than an equal volume of said matter and designed to float thereon into a position wherein it engages the valve seat to close the passage.
27. In an extruding machine, a chamber, a plurality of pumps disposed around the chamber and communicating therewith, and a common manifold for supplying the pumps with matter to be extruded.
28. In an extruding machine, a chamber, a plurality of pumps disposed around the chamber and communicating therewith, a common manifold for supplying the pumps with matter to be extruded, and a plurality of check valves associated with the manifold for preventing a back flow into the manifold from the pumps.
29. In an extruding machine, an annular chamber, a plurality of cylinders disposed around the axis of the chamber and substantially parallel therewith, each cylinder communicating directly with the annular chamber, a plunger in each cylinder, means for reciprocating the plungers, a common manifold for supplying the cylinders with matter to be extruded, and a check valve for each cylinder for preventing a back flow into the cylinder from the chamber.
30. In an extruding machine, an annular chamber, a plurality of cylinders disposed around the axis of the chamber and substantially parallel therewith, each cylinder communicating directly with the annular chamber, a plunger in each cylinder, means for reciprocating the plungers, a common manifold for supplying the cylinders with matter to be extruded, means for preventing a back flow from the cylinders into the manifold, and means for preventing a back flow from the chamber into the cylinders.
31. A method of continuously extruding matter, which consists in forcing fused matter into a chamber, causing the solidification of said matter by surrounding said chamber on opposite sides with a cooling medium, and forcing said solidified matter through an extruding aperture to reduce its cross section due to the introduction of fused matter.
32. A method of continuously extruding matter, which consists in forcing fused matter into a chamber, causing said matter to solidify, and forcing said solidified matter through the chamber due to the introduction of additional fused matter therein in a direction substantially parallel to the direction of its movement through said chamber to reduce its cross-section.
33. A method of continuously extruding matter, which consists in introducing fused matter into a chamber, allowing said matter to solidify therein, and forcing the solidified matter through the chamber solely by the subsequent introduction of fused matter to effect a reduction in the cross-section of the solidified matter.

34. In an extruding machine, a die, a chamber associated with said die, and means for forcing fused matter into said chamber where it solidifies and is thereafter forced through said die due to the introduction of an additional quantity of fused matter.
35. In an extruding machine, a die, a core tube associated with said die, a chamber surrounding said core tube, and means for forc-

ing the fused matter into said chamber where it solidifies and is thereafter forced through said die to a thickness dependent upon the relative positions of the core tube and die by pressure exerted due to the introduction of an additional quantity of fused matter.

In witness whereof, I hereunto subscribe my name this 23rd day of April, A. D. 1924.

JOHN EDSON BOYNTON.
